TENT FOR GAS-DELIVERING APPARATUS

Jay A. Heldbrink and Burt J. Clark, Minneapolis,
Minn.

Application October 7, 1931, Serial No. 567,404

1 Claim. (Cl. 128—191)

Our invention relates to tents for gas-delivering apparatus. An object of the invention in general is to provide a device in the nature of a tent for enclosing at least the head of the patient to whom the gas is to be delivered. Oxygen therapy is administered in this way for pneumonia patients, for patients with certain heart diseases, in cases of monoxide poisoning, for immediate care of new born babes, etc. In the operation of the device, we provide suitable means for supplying gases such as oxygen to the tent and means for circulating the gases from the tent through a cooler back to the tent in order to supply cooled gases to the patient. Special objects of the invention are to provide a construction by means of which the tent may be rotated and by means of which it may be universally tilted, and by means of which it may be placed in compact relation to the gas-delivering apparatus when not in use.

The full objects and advantages of our invention will appear in connection with the detailed description thereof, and the novel features of our inventive idea will be particularly pointed out in the claim.

In the accompanying drawings which illustrate a practical embodiment of our invention, Fig. 1 is a perspective view showing the device connected to a gas-delivering apparatus. Fig. 2 is a view partly in side elevation and partly in section showing the upper portion of the device. Fig. 3 is an enlarged vertical sectional view showing a portion of the device. Fig. 4 is a view in section on the line 4—4 of Fig. 2. Fig. 5 is a detail view taken at right angles to Fig. 3 and with certain portions removed. Fig. 6 is a view in section on the line 6—6 of Fig. 3. Fig. 7 is a detail view of a special collar.

Referring to the construction shown in the drawings, the numeral 10 designates the base or supporting portion of a gas-delivering apparatus of standard or any suitable construction. The base 10 is mounted on caster wheels 12 in order that the apparatus may be readily moved into any desired position to accommodate it to the patient. As shown in Fig. 1, the gas-delivering apparatus includes an oxygen tank 14, a carbon dioxid tank 16, a motor 18, a tank 20 for ice, a tank 22 for soda-lime, and customary or suitable gauges, indicators, and connections. Extending up from the base is a hollow standard 23 into the upper portion of which a rod 24 fits slidably and adjustably, being held in properly adjusted position by a handscrew 25 as shown in Fig. 2. The upper end of the rod 24 carries a support 26 provided with a horizontal cylindrical portion 28. A rod 30 passes

through the cylinder 28 and is supported for turning and sliding movement by ballbearings 32 and is adapted to be clamped in desired position by a handscrew 34. A forked member 36 is secured at its middle to the rear end of the rod 30 by a clamp 38. The ends of the forked member 36 carry elbow members 40. A hose section 42 is connected to the lower end of one of the elbow members 40 while a hose section 44 is connected to the other end of said elbow member. The hose sections 42 and 44 constitute a gas-supply pipe line. A hose section 46 is connected to the lower end of the other one of the elbow members 40 while a hose section 48 is connected to the other end of said elbow member. The hose sections 46 and 48 constitute a gas-return line.

The front end of the rod 30 has a casting 50 secured thereto, the construction of which is best shown in Fig. 3. The lower end of the casting 50 contains a threaded recess which receives the upper threaded end of a short rod 52 which extends down through a central opening in the upwardly deflected central portion of a disk 54, the periphery of said opening being formed with a knife edge 56. The rod 52 just below the knife edge 56 is surrounded by a collar 58, the upper end of which as best shown in Fig. 7 is provided with a beveled peripheral flange 60 which rests against the lower surface of the knife edge 56. A coiled spring 62 surrounding the rod 52 is interposed between the flange 60 and an enlargement 64 carried by the lower end of the rod 52. A pin 66 extending up from the disk 54 is straddled by two projections 68 extending out from the casting 50 whereby the disk 54 is prevented from turning with relation to the casting 50. The forward end of the hose section 44 is attached to a hollow member 70 which extends snugly through an opening in the disk 54 and has a downward extension 72 as shown in Fig. 6, so that the cooled gas is supplied somewhat below the top of the tent while the warmer gas is taken from the top portion of the tent through a hollow member 74 which extends snugly through another opening in the disk 54 and has the forward end of the hose section 48 attached thereto. A ring 76 is secured to the lower face of the disk 54 at the periphery thereof to provide a circumferential groove which rotatably receives a ring 78 to which is secured an annular top member 80 of a tent, the body portion 82 of which consists of any suitable fabric material. The upper end of the body member 82 is secured by a strap 84 to a depending annular flange 86 formed on the periphery of the 110

top member 80. The upper portion of the body member 82 is provided with a window 88 formed from transparent material such as celluloid. The lower portion of the body member 82 is provided with tucks 90 which when the device is in use are adapted to rest upon the covering of a bed.

The operation and advantages of our invention will be understood in connection with the foregoing description. In a preferred manner of using the device, oxygen or other gas is administered to a patient while lying in bed, the tent enclosing the head of the patient and the lower portion of the tent being tucked under the patient, the bed clothing or the pillow so that the gas will not readily escape at the bottom of the tent. The gas is delivered to the patient through the pipeline 46-48 and is returned through the pipeline 42-44 to be cooled by the ice tank 20 and purified by the soda-lime tank 22. The gas-delivering apparatus may be placed at either side of the bed or adjacent the head thereof, and by means of the handscrew 25 the tent may be secured at the proper height and in the proper angular relationship to the standard 23. The fixed attachment of the central disk 54 and the rotatable mounting thereon of the body portion of the tent constitute an important feature of this invention, since such construction permits rotation of said body portion to bring the window 88 into proper position in regard to light. This rotating action avoids the necessity of putting more than one window in the tent to accommodate the light for different positioning of the bed. At the same time, the fixed positioning of the disk 54 with relation to the hose connections 44 and 48 prevents these connections from being

twisted or subjected to undue strain when the tent is rotated. From an inspection of Figs. 2 and 3, it will be understood that the tensioned supporting of the tent through the spring 62 permits canting or tilting of the tent in every direction. The engagement of the beveled flange 60 with the lower portion of the knife edge 56 provides for a ready universal tilting movement of the tent so that changes in the position of the patient are taken care of. When the device is not in use, the hand screw 34 may be loosened and the supported rod 30 slid rearwardly in the cylindrical member 28. This permits the tent to be brought close to the gas-delivering apparatus thereby economizing space. The attachment of the hose sections to the fork 36 carried by the rear end of the rod 30 prevents them from being subjected to strain when the device is placed in the folded position referred to and also provides for keeping the hose connections taut when adjusting the distance of the tent from the gas apparatus.

We claim:

A tent for gas-delivering apparatus comprising a central enclosing top member, a support for said member, an annular top member disposed around said central member, one of said top members having a circular groove at its margin into which the adjacent margin of the other member fits rotatively in gas tight manner, an enclosing wall structure depending from the outer margin of said annular member, and supply and return gas connections for said enclosing structure extending through said central member.

JAY A. HEIDBRINK.
